HENRY HELLWEG, OF MILWAUKEE, WISCONSIN, ASSIGNOR TO SAMUEL D. PAGE AND COMPANY, OF DES MOINES, IOWA, A COPARTNERSHIP CONSISTING OF SAMUEL D. PAGE AND CHARLES HERKNER.

LOOSE-LEAF BINDER.

1,068,127.

Specification of Letters Patent. Patented July 22, 1913.

Application filed February 6, 1911. Serial No. 606,709.

To all whom it may concern:

Be it known that I, HENRY HELLWEG, of Milwaukee, Wisconsin, have invented a Loose-Leaf Binder, of which the following 5 is a specification.

This invention relates to loose-leaf binders of the telescoping type, in which a pair of back-plates, which may or may not be made with angular extensions covering the 10 back edge of the book, are held together in variable relation by means of a plurality of telescopic posts, said posts being made in two sections one of which slides within the other, and is provided with means for securing it thereto in any desired position of extension.

A common means of clamping the two sections of the back consists in screw-posts operating within the post-sections, each 20 screw-post turning in the larger section, and engaging a thread on the end of the smaller section. On account of the fact that the screw-post has to operate the entire length of the smaller section, it is necessary either 25 to thread it for such length, or else to ream out the outer end of the post to avoid the threading operation. Either operation, when the post is made of metal tubing as is customary, is expensive and it is one of the 30 objects of this invention to provide a cheaper construction.

Another object of this invention is to provide means for strengthening and solidifying the post, and I do this by providing a 35 web near the outer end of the outer telescoping-section thereof, between it and the back-flange of the back-plate, in a manner which will be hereinafter more particularly described and set forth in my claims.

40 In the accompanying drawings, I have illustrated the most improved form of my invention in various views and sections, and herein—

Figure 1 is a vertical transverse section 45 on a magnified scale of a binder-back constructed according to my invention, through the axis of one of the posts; the metal only being shown, and the pasteboard and cloth filling and covering omitted. Figs. 2 and 50 3 are longitudinal fragmentary sections through the back on the planes 2 and 3 respectively; Figs. 4 and 5 are horizontal sections through the same parts on the planes 4 and 5 respectively; Fig. 6 is a perspective

view of an inner post-section as partly finished and ready for tapping and riveting to the back-plate; and Fig. 7 illustrates a pair of dies to show how the crimped end of the inner post-section is formed.

The back-plates are designated respectively A and B, said back-plates being provided in this case with telescoping back-flanges a' and b' , which cover the back edge of the book. Only one of the sectional posts is shown, as it will be understood that two 65 or more of such posts will ordinarily be as usual used for each binder.

Each post comprises outer and inner telescoping-sections C and D, said telescoping-sections being secured at their ends to the 70 back-plates, and for this purpose being provided with the form of fastening described and claimed in my copending patent application filed of even date herewith, said fastening comprising a pair of tangs or ears 75 c' , d' formed by cutting away the metal from opposite sides of the end of the post-section, said tangs or ears being subsequently bent outwardly, and passing through slots a^2 , b^2 formed in the back-plates to receive them, and the ends of said tangs or ears being subsequently clenched upon the outer face of the back-plates as shown. However, this form of fastening is not essential to the construction of the elements, to 85 which the present invention more particularly relates.

To secure the two post-sections together in variable relation is used the screw-post E having on its upper end the manipulating 90 handle e' . This screw-post is such as is ordinarily used, the peculiar feature relating thereto being the means by which it is caused to engage the upper end of the post-section D. Instead of making the post-section D of 95 a smaller diameter than the screw-post, so that it can be and must be threaded and reamed for its entire length, I make the post-section of large enough diameter so that the screw-post fits loosely therein, and I compress the upper end of the post in the manner illustrated more particularly in Fig. 6, so as to form a tubular portion d^2 of smaller diameter, which can be tapped to the thread of the screw-post E, as shown in Fig. 1; the 105 surplus metal being disposed in the form of crimps d^3 . I have found it is best to do this by means of the pair of dies F, G shown in

Fig. 7, which represents the end of the post-section D between them ready to be compressed. When the die G descends to the position shown in the dotted lines, the end 5 of the post-section will have assumed the form shown at d^2 , d^3 in Fig. 6. This method completely avoids the necessity of the reaming operation, and makes it only necessary to tap the short compressed portion d^2 , thus 10 saving much labor and material.

With regard to the outer post-section C, it is to be observed that in my present invention this is not made of seamless metal tubing as usual, but is made of sheet-metal 15 rolled into the form of a tube with abutting edges c^2 at the back; and its rigidity is reinforced by means of a web formed of flange-like extensions c^3 on the two edges c^2 at or near the free end of the post. Said 20 extensions c^3 are provided with shoulders c^4 on their edges at the point where they meet the back-flange b' of the back-plate B, and beyond this with ears c^5 which pass through a slot b^3 in the flange b' and are bent over 25 flat upon the outer face thereof, as clearly shown in Fig. 5. This makes a strong and rigid connection between the back-flange b' and the post, and the latter is therefore not dependent upon its end fastenings c' , d' to 30 keep it in line. The back-flange b' has preferably a depression b^4 pressed thereinto to receive the ears c^5 flush on the outer side, so as to avoid their projection beyond the face, and this also forms a sort of basin which 35 may receive and be filled with the solder H. It should be understood, however, that the strength of my reinforcement is in no wise dependent upon soldering.

From the above description it will be 40 readily seen that my invention is not limited to special forms and mechanical constructions such as I have hereinabove shown by way of illustration, but that the principles thereof are expressible in a variety of ways 45 as will be well understood by those skilled in the art; therefore the scope of my claims is to be interpreted in view of such alternative construction.

Having thus described my invention, what 50 I claim as new and desire to secure by Letters Patent is:

1. In a loose-leaf binder, in combination with a flanged back-plate, a reinforced post-section having a web connecting its outer 55 end with the flange of the back-plate; said back-flange having a slot therein and said web having ears upon its end which pass through said slot and are spread upon the outer side thereof.

60 2. In a loose-leaf binder, in combination with a flanged back-plate, a reinforced post-section having a web connecting its outer end with the flange of the back-plate; said back-flange having a slot therein and said 65 web having ears upon its end which pass

through said slot and are spread upon the outer side thereof, there being an abutment shoulder upon the edge of said web at the base of said ears.

3. In a loose-leaf binder, in combination 70 with a flanged back-plate, a reinforced post-section having a web connecting its outer end with the flange of the back-plate; said back-flange having a slot therein and said web having ears upon its end which pass 75 through said slot and are spread upon the outer side thereof, the back-plate being formed with a basin-like depression surrounding and containing said ears flush with the outer surface of the back-flange. 80

4. In a loose-leaf binder, in combination 85 with a flanged back-plate, a reinforced post-section having a web connecting its outer end with the flange of the back-plate; said back-flange having a slot therein and said web having ears upon its end which pass 90 through said slot and are spread upon the outer side thereof, the back-plate being formed with a basin-like depression surrounding and containing said ears flush with the outer surface of the back-flange and said depression being filled with solder which unites said ears to the back-plate. 95

5. In a loose-leaf binder, the combination 100 with a flanged back-plate of an outer post-section secured thereto at its base and formed of sheet-metal bent into cylindrical form with abutting edges, said abutting edges being opposite the back-flange of the back-plate; the free end of the post being provided with flanged extensions extending 105 from said abutting edges to the back-flange and having one or more shoulders which abut thereagainst; and beyond said shoulders a pair of ears passing through a slot in said back-plate and spread upon the outer side of the back-plate. 110

6. In a loose-leaf binder, the combination 115 with a flanged back-plate of an outer post-section secured thereto at its base and formed of sheet-metal bent into cylindrical form with abutting edges, said abutting edges being opposite the back-flange of the back-plate; the free end of the post being provided with flange-extensions extending 120 from said abutting edges to the back-flange and having one or more shoulders which abut thereagainst; and beyond said shoulders a pair of ears passing through a slot in said back-plate and spread upon the outer side of the back-plate, and said back-flange being provided with a basin-like depression which receives and contains said ears flush with the outer surface of the back-plate. 125

7. In a loose-leaf binder, the combination 130 with a flanged back-plate of an outer post-section secured thereto at its base and formed of sheet-metal bent into cylindrical form with abutting edges, said abutting edges being opposite the back-flange of the 135

back-plate; the free end of the post being provided with flange-extensions extending from said abutting edges to the back-flange and having one or more shoulders which 5 abut thereagainst; and beyond said shoulders a pair of ears passing through a slot in said back-plate and spread upon the outer side of the back-plate, and said back-flange being provided with a basin-like depression 10 which receives and contains said ears flush

with the outer surface of the back-plate, and solder filling said depression and uniting said ears and back-flange together.

In witness whereof I have hereunto set my hand in the presence of two witnesses. 15

HENRY HELLWEG.
